UNITED STATES PATENT OFFICE

2,609,173

MANUALLY ADJUSTABLE CHOKE VALVE

Carl S. Weyandt, Homer City, and Neville C. McKelvy, Blairsville, Pa., assignors to Sytron Company, Homer City, Pa., a corporation of Delaware

Application August 3, 1946, Serial No. 688,186

1 Claim. (Cl. 251—11)

1

This invention relates generally to improvements in carburetors and more particularly to improvements in choke valves on carburetors for internal combustion percussion hand tools such as gasoline hammers.

Percussion hand tools are employed for breaking rock, concrete, cutting asphalt, drilling, digging or spading shale or clay, and for tamping, driving ground rods or sheathing and other similar work. A percussion hand tool is a self-contained machine that does not rely on a central power system or plant as do the electric or pneumatic hand tools.

An internal combustion percussion hand tool is a complete combustion engine comprising a cylinder with a single combustion chamber having an idling captive piston and a free percussive piston operating therein. The idling captive piston operates the magneto and supplies cooling air. The free percussive piston provides the repeated blows on the tool bit to produce useful work. This hand tool is provided with a fuel tank for supplying the carburetor and has a handle at the top with which to manipulate it while operating. However this hand tool has limitations as to the angle in which it may be used owing to the fact that it is supplied with fuel by means of a carburetor. By mounting the carburetor with the axis of the bowl at an angle to the axis of the cylinder this hand tool may be operated when disposed in a horizontal position.

The violent vibrations created by the free percussive piston and the relatively large combustion chamber produce many problems not ordinarily encountered with internal combustion engines and this invention is directed to improvements in carburetor choke valves for this percussion tool.

Another object is the provision of a manually operated latch for retaining the choke valve in its open position to prevent accidental closure due to vibration.

Other objects and advantages appear herein-after in the following description and claim.

A practical embodiment illustrating the principles of this invention is shown in the accompanying drawings wherein:

Fig. 1 is a view partially in section of the carburetor.

Fig. 2 is a top plan view of the carburetor shown in Fig. 1.

Fig. 3 is a sectional view taken on the line 3—3 of Fig. 2.

Fig. 4 is an enlarged detailed view partly in

section showing the detent engaging the cam with the choke valve in another position than that illustrated in Fig. 1.

The carburetor shown in Figs. 1 to 4 is provided with the body member 50 having a straight throat 51 which is enlarged at the inlet end as indicated at 52 for the purpose of receiving the choke valve 53. The inlet and outlet mouths 54 and 55 of the throat 51 are flanged. The faces 10 of these flanges are parallel with each other but their planes are disposed at an angle to the throat to permit the percussion tool to be operated in a horizontal position.

The underside of the carburetor body 50 is 15 provided with an annular seat 56 to receive the fuel bowl 57. An integral depending portion 58 extends from the underside of the body 50 to within the bowl and is provided with the centrally disposed threaded hole 60 for receiving the screw 61 which holds the bowl in place. The screw 61 has an axial and lateral pasageway 62 for connecting the inner end of the threaded hole 60 to the interior of the bowl. This passage in the bolt 61 permits the drilling of a straight bore 63 from the throat 51 through the body to the inner end of the hole 60. The outer end of the bore is provided with the idling jet nozzle 64. Thus the idling jet is straight, connecting a relatively large chamber, represented by the inner end of the hole 60, to the throat. It leans toward the outlet mouth and does not require piercing of the other side of the body as the drill may be inserted through the mouth 55 to form the bore 63. This provides a more efficient and more compact carburetor unit as the idling jet 30 may be placed closer to the throttling valve 65 and the outlet mouth need only extend sufficiently to allow clearance for the bowl seat 56. The bore of this idling jet is relatively large to provide a rich mixture of gasoline for idling because the combustion chamber is very large when the engine is started and permitted to idle. The sloping of the straight bore of the idling jet provides better flow of the fuel.

45 The shaft of the throttling valve 65 has a lever secured thereto for operating the same. The running jet 66 is formed by drilling a straight bore 67 from the top of the body 50 through the venturi 68 in the throat 51 and through the depending portion 58 to the bottom thereof. A nozzle 70 is secured in the bore 67 and is arranged to hold the venturi 68 in position if it is a separate body as shown. However this venturi 50 is preferably made as an integral part of the die cast body 50.

The running jet needle valve 71 is threaded to be received in the threaded bushing 72 in the usual manner and the outer end of the needle valve is provided with the adjusting knob 73. When the needle valve is properly adjusted on the tool a limiting flange or sector 74 is secured to the knob 73 and its end faces are arranged to engage the stop 75. The adjustment of the needle valve permitted by the stop is sufficient to regulate the engine for better operating conditions from day to day, depending upon the atmospheric condition, but this adjustment is insufficient to prevent the engine from operating at either limit. This stop also prevents the terrific vibration of the tool from changing the needle valve adjustment beyond the range of the shoulders thereon. However a forked extension rod may be inserted in the holes in the knob 73 of Fig. 2 and extend upwardly to permit the operator to manually adjust the needle valve 71 while the tool is operating.

The shaft of the choke valve 53 has the integral cam member and lever 76 secured thereto. The cam member has spaced projections 77 and 78 between which are a series of seats arranged to be engaged by the ball of the detent 80 for holding the choke valve at any one of the positions represented by the seats. However the vibration of the percussion tool may cause this valve to move around even though a heavy spring is employed in the detent. The spring latch 81 is arranged to engage the cam projection 77 and thereby provide a positive latch for holding the choke valve in its open position. A finger projection 82 is secured to the latch 81 to permit the index finger to release the latch by raising it above the projection 77 while the thumb moves the lever and the valve in a counterclockwise direction to close the choke valve. Otherwise the latch 81 will maintain the choke valve in its open position as the vibrations of the tool are unable to deflect the spring latch 81 sufficiently to release the choke valve.

The fuel bowl is provided with the hinged float 83 arranged to actuate the gasoline inlet valve 84 that regulates the flow of fuel from a tank through the line 42. In cold weather the spring

latch 81 may be readily raised to partially close the choke valve and enrich the mixture to start the engine. After it has warmed up the choke valve is opened and the latch automatically drops back into place.

We claim:

A manually-operated choke valve for a carburetor supplying fuel to an internal combustion percussion hand tool, comprising a casing in which said choke valve is mounted, a cam fixed to move with the choke valve and having spaced projections with a series of seats therebetween, a spring loaded ball detent engaging said seats to hold said valve at different positions between its open and closed position, and a flexible arm on said casing to engage one of said projections and lock the valve in its fully open position.
